No. 15,652.

Patented Dec. 30, 1884.

UNITED STATES PATENT OFFICE.

ALFRED HEALD, OF PHILADELPHIA, PENNSYLVANIA.

DESIGN FOR A CARPET.

SPECIFICATION forming part of Design No. 15,652, dated December 30, 1884.

Application filed November 10, 1884. Term of patent 3½ years.

To all whom it may concern:

Be it known that I, ALFRED HEALD, a citizen of the United States, and a resident of Philadelphia, Pennsylvania, have invented or 5 produced a new and original Design for a Carpet-Pattern, of which the following is a specification.

My design for a carpet-pattern is fully shown in the accompanying photograph. 10 The design for the body of the pattern consists of representations of stems with masses of leaves and flowers, and with smaller stems, buds, and blossoms filling in the groundwork. Outside of the body is the border, having on 15 the inside a narrow band and on the outside a wider band. The central strip of the border has floral ornamentation of the same general character as that of the body of the carpet, and the inner and outer bands are ornamented with figures, too fully shown to need 20

detailed description, the general features of the entire ornamentation being in the Hindoo or East India style.

I claim—

1. The design for a carpet-pattern, said design consisting of the central or body portion, having the floral ornamentation shown and described. 25
2. The design for a carpet-pattern, said design consisting of a central strip with floral ornamentation, and inner and outer bands with ornamentation, as shown and described. 30

In testimony whereof I have signed my name to this specification in the presence of two subscribing witnesses.

ALFRED HEALD.
